ROYDEN A. BLUNT, OF BALTIMORE, MARYLAND

METHOD OF ELIMINATING SOOT

Application filed March 31, 1927. Serial No. 180,050.

This invention relates to the art of fuel burners and more specifically to a method of and apparatus for removing deposits of soot in gas producer lines.

5 It has heretofore been customary to remove accumulations of soot by raking out or blowing out with steam, but both of these methods are objectionable, since raking out is difficult and expensive and still leaves the 10 ultimate elimination of the soot to be provided for, and blowing out with steam discharges the soot into the atmosphere unburned with a consequent pollution of the surrounding territory.

15 By my present invention I introduce a large volume of low pressure air which burns the soot progressively from the point of intake of the blower air up to the end of the line, and results in the combustion of substantially all of the soot by the time the top 20 of the stack is reached. During this operation a very high heat is generated and it is necessary to carefully regulate the volume of air so as to provide sufficient oxygen for 25 complete combustion, and at the same time regulate the pressure so as not to propel the soot into the atmosphere unburned, and not to generate such a great degree of heat that the metal and refractory parts of the system 30 will be damaged.

It is therefore an object of this invention to provide a new and improved method of soot elimination.

It is another object of this invention to 35 provide an apparatus for carrying out this method.

It is also an object of this invention to perform these operations without discharging the soot into the atmosphere unburned and 40 without damaging the gas main.

It is another object of my invention to 45 perform the burning out operation without shutting down the operation of the furnaces or lehrs which are ordinarily heated by the producer gas, and to cool the main as the burning out is being effected.

With the above and other objects in view, which will be apparent as the description proceeds, I have set forth my invention in 50 the following specification taken in connec-

tion with the accompanying drawing, in which:

Fig. 1 is a diagrammatic plan view of my improved apparatus, and

55 Fig. 2 is a vertical section through a portion of my apparatus on the line 2—2 of Fig. 1, on an enlarged scale.

Fig. 3 is a vertical section through a portion of my apparatus on the line 3—3 of Fig. 1, on an enlarged scale.

60 My invention is particularly adapted for the removal of products of combustion from producer gas mains. In these there is a heavy accumulation of soot, which is of a loose, light and flaky nature, so that it is easily blown out into the atmosphere if any considerable pressure is applied to it. This 65 accumulation is so rapid that after operation for a week the mains are often filled with it to one-third of their capacity, thus impairing the efficiency of the gas main and making it necessary to remove this accumulation.

70 I have discovered that this can be done, without discharging the soot into the atmosphere, and without damaging the line, by using a large volume of low pressure air.

While the volume and pressure vary for different installations, and especially with the length 75 thereof, I have found that a volume of from forty to fifty thousand cubic feet of air per minute, and a pressure of three-fourths of an inch of water, are satisfactory for most

80 purposes, and particularly for installations using mains of 6 to 8 feet diameter and 700 or 800 feet in length with several outlets therefrom.

If a pressure greater than one and one-half inches of water is used, the 85 temperature which is generated by the combustion of the soot is ordinarily so great that the metal and refractory parts of the producer lines are damaged.

Referring to the accompanying drawing, I have illustrated therein the general arrangement of a producer gas main 10 and a series of furnaces 11 and lehrs 12 heated by the producer gas conveyed by said main.

Each of the furnaces and lehrs is provided with a cut-off damper 13, to prevent communication between them and the main at predetermined times, and each of the furnaces and lehrs is also provided with gas or oil burners 14 for heating them independent-

90 ly of the producer gas during the burning 95 of the furnaces and lehrs.

100

- out period. At suitable points in the line, stacks 15 communicate with the atmosphere and each of these stacks is preferably provided with a cut-off damper 16 adjacent to its connection with the main 10. The producer gas is supplied to the main at 17 from any suitable gas producer, or gas producers (not shown), and the main may be shut off from the latter by a damper 18.
- 10 The air is supplied by a blower fan 21, of any well known type capable of handling a large volume of low pressure air, which is connected with one end of the producer main.
- 15 When a sufficient amount of loose soot has accumulated in the latter to warrant its removal, the dampers communicating with the producers, furnaces and lehrs are closed, the dampers communicating with the stacks are either left completely open or partially throttled, as will be explained later, and the blower is started at such a rate that it will deliver from 40,000 to 50,000 cubic feet of air per minute at a pressure of approximately 20 $\frac{3}{4}$ of an inch to $1\frac{1}{2}$ inches of water. The incoming air starts the hot soot rolling along the main and the combustion begins to take place without the application of any external heat. This generates additional heat and the burning out is progressive throughout the main, succeeding portions of the incoming air furnishing the necessary oxygen for the combustion of the soot contained in succeeding portions of the main and effecting a cooling of those portions of the main from which the soot has previously been burned out, with the result that substantially all of the soot in the main is gradually burned before it can emerge from the stack.
- 25 Inasmuch as the soot is practically pure carbon, no residue is left.
- 20 A sufficient volume of air must be introduced to carry all the soot along with it and to provide sufficient oxygen to promote the combustion of all of the soot. At the same time the air pressure must be low enough to prevent blowing the loose, flaky soot into the atmosphere unburned. The volume of air introduced can be controlled at the blower by regulating its speed and by throttling it by a slide control 22.
- 25 This regulation of the volume of air at the blower also affects the pressure developed in the line. Consequently, if too great a pressure is being developed, it can be reduced by partially throttling the blower. A similar reduction in the pressure can also be accomplished by opening the stack dampers.
- 30 The temperature developed in the main increases with the volume and pressure, and with the length of the main, and is highest at the end farthest from the inlet of the blower air. It has been found that in a long main a pressure of as much as $1\frac{1}{2}$

inches of water, coupled with a volume of from 40,000 to 50,000 cubic feet of air per minute, will develop a temperature of approximately 2800° F., which is sufficiently high to cause gradual deterioration of the gas main by opening up seams therein, by burning the metal framework, and by breaking down the efficiency of the refractory parts. I have therefore found it desirable, when using the above volume of air in a long main, such as that described above and illustrated herein, to reduce the pressure to $\frac{3}{4}$ of an inch of water, and I have found that this can be most effectively done by throttling the blower and leaving the stack dampers wide open. Under these conditions a temperature of from 2400° to 2500° F. is developed at the hottest period.

70 I have found that in such installation the soot can be effectively removed by burning out the main in the manner indicated herein for a period of about 45 minutes per week. During the burning out it is not necessary to shut down the operation of the furnaces and lehrs which are normally heated by the producer gas; as their operation can be continued by lighting the gas or oil burners 14.

75 I have also found that when excessive temperatures are developed at various points in the line, these temperatures can be lowered by injecting small amounts of steam into that portion of the line, as by the nozzles 23. This steam acts as a cooling agent and absorbs the excess sensible heat.

80 In Fig. 2 I have shown the construction of one form of gas producer main. This consists of a steel shell 31, immediately inside of which is placed a lining of sil-o-cel bricks 32, and inside of the latter is placed a lining of fire bricks 33. The sil-o-cel bricks and the refractory bricks are each luted together in the regular manner.

85 By the term "hot soot," as used herein, I mean that the soot is at the temperature of 90 its ignition.

95 From the above description it will be apparent that I have solved the difficult problem of disposing of loose soot, which is an inherent disadvantage in the use of producer gas, without discharging this soot into the atmosphere unburned, thus making it possible for industries located in cities, as well as those in rural districts, to avail themselves of this cheap source of fuel without conflict with the municipal regulations on soot disposal, and that the burning out operation may be carried on simultaneously with normal production in the factory in which the burning out is to be effected, thus 100 resulting in a considerable saving of time and money.

105 It will also be obvious that my invention can be applied with equal efficiency to shorter and less complicated mains than that

illustrated and described herein, and that the connections and arrangement of the various parts of my apparatus may be varied in many ways within the scope of the following claims.

5 I claim:

1. The method of eliminating loose hot soot at the temperature of ignition in the presence of air from gas producer mains, which comprises blowing into the main over 10 40,000 cubic feet of air per minute at a pressure of less than 2 inches of water, and thereby burning the soot within the main without discharging it into the atmosphere.
- 15 2. The method of eliminating loose hot soot at the temperature of ignition in the presence of air from gas producer mains, which comprises blowing into the main from 40,000 to 50,000 cubic feet of air per 20 minute at a pressure of approximately $\frac{3}{4}$ of an inch of water, and thereby burning the soot within the main without discharging it into the atmosphere.
